(57) **CLAIM**

The ornamental design for water filter fitting, as shown and described.

DESCRIPTION

FIG. 1 illustrates a front perspective of one of the fittings of a water filter.

FIG. 2 illustrates a front view of the fitting illustrated in FIG. 1.

FIG. 3 illustrates a back view of the fitting illustrated in FIG. 1.

FIG. 4 illustrates a first side view of the fitting illustrated in FIG. 1.

FIG. 5 illustrates a second side view of the fitting illustrated in FIG. 1.

FIG. 6 illustrates a top view of the fitting illustrated in FIG. 1.

FIG. 7 illustrates a front perspective view of the fittings on an implementation of a water filter.

FIG. 8 illustrates a front view of the fittings on the implementation of a water filter illustrated in FIG. 7.

FIG. 9 illustrates a back view of the fittings on the implementation of a water filter illustrated in FIG. 7.

FIG. 10 illustrates a first side view of the fittings on the implementation of a water filter illustrated in FIG. 7.

FIG. 11 illustrates a second side view of the fittings on the implementation of a water filter illustrated in FIG. 7.

FIG. 12 illustrates a top view of the fittings on the implementation of a water filter illustrated in FIG. 7.

FIG. 13 illustrates a bottom view of the fittings on the implementation of a water filter illustrated in FIG. 7.

FIG. 14 illustrates a front perspective view of the fittings on an implementation of a water filter; and,

FIG. 15 illustrates a front perspective view of the fittings on an implementation of a water filter.

The broken lines, when present in the drawings, represent portions of the water filter. The broken lines are for the purpose of illustrating the environment of the design and form no part of the claimed design. The surface shading lines, when present in the drawings, show contour and/or distinguish between open and solid areas. The surface shading lines are not surface ornamentation. The design is not limited to the scale shown herein.
